United States Patent Office

Des. 228,606

Patented Oct. 16, 1973

228,606

TRAY

Gerald F. Blount, Milwaukie, Oreg., assignor to
Peco, Inc., Portland, Oreg.

Filed Sept. 13, 1972, Ser. No. 288,724

Term of patent 14 years

Int. Cl. D7—99

U.S. Cl. D7—37

FIG. 1

FIG. 2

FIG. 3

FIG. 1 is a top perspective view of a tray showing my new design; the end of the tray opposite that shown in FIG. 1 being a mirror image of the disclosed end;

FIG. 2 is a rear edge view of the tray shown in FIG. 1; and

FIG. 3 is a bottom view of the tray.

I claim:

The ornamental design for a tray, as shown and described.
